UNITED STATES PATENT OFFICE.

GAIUS A. BRAUN, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

AIR-COOLING GARMENT PRESS.

Application filed October 30, 1924. Serial No. 746,756.

This invention relates to garment pressing machinery and more particularly to an improved air cooling garment press wherein the garment or work is removed from the 5 press jaws and cooled by air subsequently to being steam treated and pressed.

An object of the invention is to produce an improved air cooling and air drying means combined with an ordinary steam 10 pressing machine in order that the work be quickly cooled and made ready for wearing or boxing and packing subsequently to the heating, pressing, and steam spraying operations, the characteristic being that no time 15 is lost in the airing of the garment since my invention affords means external of the pressing head and buck for accomplishing this purpose; and the drying and cooling of the work not being carried out while inside the 20 press thus frees the press for the next pressing operation.

The accompanying drawings illustrate an embodiment of the invention serving to illustrate the principles involved, but it is understood that changes may be made to better 25 adapt the invention for use in connection with standard type pressing machines.

Figure 1 illustrates a fragmentary plan view of the improved garment pressing machine showing an upper surface foraminous press head adapted to circulate air through the work placed on top of the press head subsequently to the pressing operation between the pressing jaws.

Figure 2 is a side fragmentary view of the pressing machine with the head of the press shown in section as developed on the line 2-2 of Figure 1.

Figure 3 illustrates a fragmentary detail 40 of the head to better explain a novel work holding clamp employed to hold the work in place during the cooling operation and during the opening and closing of the press.

Referring now more particularly to the 45 drawings for a further description of the invention, there is illustrated a frame 10 of any suitable design and the frame supports the usual form of press buck or jaw 11 which is heated by any suitable means as for example steam or electricity. The frame supports a swinging press lever 13 pivoted at 14, and the rear portion of the press lever is broken away, though it is to be understood that suitable mechanism may be employed

for swinging the press lever on the fulcrum 55 point 14 to raise and lower a pressing head 15 supported on the front end of the lever.

It is preferred that the press head 15 have an upper flat surface which is unobstructed by the press lever and to this end the press 60 lever 13 may be extended outwardly to each end of the press head and is provided with a bolting flange 17 by which the forward ends of the press lever 13 are securely attached to the ends of the head 15.

The press head 15 may be provided with a steam heating chamber 19 supplied with steam lead and steam return pipes 20 connected with the heating chamber 19. The head 15 may as well, if desired, be manufactured with a steam spraying chamber by which the work on the buck 11 may be moistened and treated with steam during the pressing operation as will be understood by those versed in the art.

The press head 15 is provided with an air circulating chamber 22 and may include a nipple 23 connected with the air circulating chamber. Suitable connections, such as a flexible tube 24, are attached to the nipple 23 80 and may be connected with either a blower or exhauster in order that air be blown up through the foraminous chamber 22 or exhausted therefrom. The upper wall or surface of the chamber 22 is provided with 85 perforations 25 through which the air is discharged from the head chamber 22 or drawn thereinto. By placing the hot and steam treated work on top of the foraminous buck surface, it is possible to quickly cool the work 90 or garment while another garment is being pressed between the pressing members or jaws.

Means are provided to hold the work in position on the head 15 during the up and down swinging motion thereof, and to this end a clamp is swingably mounted on top of the head and is adapted to reach across and bear down upon the garment to hold it in position during the pressing and cooling 100 operation. This garment clamp comprises a plurality of pressure fingers or bars 27 fixed to a shaft 28, and this shaft is supported in bearings 29 anchored to the head. Since the several pressure fingers 27 are fixed 105 to the shaft, the operator may raise and lower the clamp means by grasping and moving any one of the fingers. Suitable

resilient means are employed for holding the clamp in down position or in up position. For example, a coil tension spring 30 has its lower end attached to the head 15 while its upper end is attached to a mutilated disc 31 fixed to the shaft 28. The disc 31 and shaft 28 move together and the disc is made with a notch 32 defined by a shoulder at each end. A stop pin 33 is anchored to the bearing 29 and stands rigidly alongside the notch 32 in such a manner that each shoulder end of the notch 32 impinges against the pin 33 so that the notch 32 is defined at each end by the shoulder which comes to rest against the pin 33. Since the pin 33 is anchored to the bearing 29 it remains stationary while the disc 31 with shaft 28 and pressure fingers 27, all swing relatively to the pin. The spring 30 acts to hold the pressure clamp fingers 27 down in clamping relation on a garment and likewise acts to hold the finger 27 upwardly in a vertical position as indicated in dotted lines. It is noted, therefore, how the spring 30 will maintain the clamp 27 in upright position out of the operator's way while he is placing a garment on the upper foraminous head surface, and the operator quickly snaps the garment clamp 27 down in position by pulling one of the fingers 27 forwardly which permits the spring 30 to quickly draw the clamp down on the work.

In the operation of an improved pressing machine of this character, the operator first steam presses the garment between the pressing jaws 11 and 15. This operation usually leaves the work very hot and oftentimes damp inasmuch as suits of clothes and the like are steam sprayed during the pressing operation. In some pressing machines, it has been the practice to draw air or blow air through the garment while between the press jaws, but this prolongs the period the garment is in the press so the operator, in the use of my improved machine, removes the work from the press and places it on top of the head and out of his way while engaged in pressing the next garment; and while pressing the next garment, the first one pressed is receiving a prolonged air cooling treatment.

Among the important advantages of this improvement, it is to be noted that the work receives a longer cooling treatment than ordinarily afforded by other types of air cooling pressing machines. In fact, the hot and damp garment is subjected to a cooling treatment on the upper surface foraminous head for a time equal to the steaming and pressing treatment the next garment is receiving between the jaw pressing members, and so it follows that the work, when removed from the clamps 27, is cool and dry ready for wear or ready for bundling and packing. Furthermore, the work in the

press remains between the jaws the time required for the operator to remove the cooled work from the top and in this way the garment in the press may receive a longer pressing period as well as the garment on top receiving a longer cooling period than ordinarily results in using present day machines.

What I claim is:—

1. A garment press comprising in combination, cooperating press jaws, a swinging press lever adapted to open and close the press, said press lever having its front end branched out and extended outwardly to the ends of a press jaw and joined thereto for the purpose of leaving an unobstructed upper flat surface on the jaw, said jaw being provided with an upper foraminous work cooling surface, and means for forcing air through the said upper foraminous jaw surface to cool work placed thereon. 75

2. A garment press comprising in combination, cooperating press jaws, a swinging press lever adapted to open and close the press, said press lever having the front end extended outwardly to the ends of a press jaw and joined thereto for the purpose of leaving an unobstructed upper surface on the jaw, a garment retaining means installed on the upper surface of the jaw to hold the work in place during the opening and closing motion of the press, and means to blow air through the work. 95

3. A garment pressing machine comprising in combination, cooperating press jaws, a swinging press lever adapted to open and close the press, said press lever having the front end branched outwardly and extended to the ends of one of the jaws and joined thereto for the purpose of leaving an unobstructed upper surface on the jaw, a garment retaining means installed on the upper surface of the jaw to hold work in place during the opening and closing motion of the press, and spring actuating means to hold the garment retaining means in downwardly operative position or upwardly inoperative position. 100

4. A garment press comprising in combination, cooperating press jaws, means for opening and closing the press, one of the jaws being provided with an air circulating chamber adjacent the upper wall thereof, and said upper wall being provided with perforations for admission or discharge of air to and from the chamber by means of which the work treated between the press jaws and subsequently placed upon the top jaw surface may be subjected to a cooling and drying treatment. 115

5. A garment press comprising in combination, cooperating press jaws, means for opening and closing the press, one of the jaws being provided with an air circulating chamber adjacent the upper wall thereof, 120

- 5 said upper wall being provided with perforations for admission or discharge of air to and from the chamber by which the work treated between the press jaws and subsequently placed upon the top jaw surface may be subjected to a cooling and drying treatment, and a work clamp arranged to hold the work in position over the perforations.
- 10 6. A press comprising, a cooperating head and buck between which work is pressed, said head being provided with an air chamber made in its upper portion, said air chamber of the head having an unobstructed substantially flat top surface on which a garment which is not being pressed may be placed, and said top flat surface of the head
- 15

air chamber being foraminated to permit a flow of air therethrough to cool the garment.

7. A press comprising, a cooperating head and buck between which work is pressed, said head being provided with an air chamber made in its upper portion, said air chamber of the head having an unobstructed substantially flat top surface on which a garment which is not being pressed may be placed, said top flat surface of the head air chamber being foraminated to permit a flow of air therethrough to cool the garment, and holding means mounted on top 25 of the head to clamp down the garment.

In testimony whereof I affix my signature.

GAIUS A. BRAUN.
